LASTING MACHINE

Charles A. Robinson, Salem, Mass., assignor to
 United Shoe Machinery Corporation, Flemington, N. J., a corporation of New Jersey

Application September 13, 1944, Serial No. 553,873

35. Claims. (Cl. 12—14)

This invention relates to lasting machines, and is herein illustrated as applied to a power-operated toe-lasting machine which, except as hereininafter explained, is constructed generally as disclosed in United States Letters Patent No. 2,160,846, granted on June 6, 1939, on an application of F. C. Eastman's and A. F. Pym's. It is to be understood, however, that the invention is not limited to machine organizations of that particular character.

The machine shown in the above-mentioned Letters Patent is provided with wipers which are swung upwardly about an axis extending widthwise of the last to wipe the toe-end portion of the upper heightwise of the last and are thereafter operated to wipe the marginal portion of the upper inwardly over an insole on the last, and also with grippers which apply a pull to the toe end of the upper and control it during the greater portion of the wiping operations of the wipers. The present invention, in its illustrative embodiment, provides instead of such grippers a device having the function of what is commonly known as a retarder and hereinafter so termed, this device being arranged to clamp the marginal portion of the upper outspread on the wipers about the end and along the sides of the toe and to cooperate with them in applying a pull to the upper while preventing the formation of any objectionable wrinkles therein in the course of the toe-lasting operation. Novel features of the invention are to be recognized in the construction of the retarder and of the means for operating and controlling it. As herein illustrated, the retarder comprises a plurality of spring-controlled upper-clamping members arranged in a series about the end and along the sides of the toe and relatively movable heightwise of the last to adjust themselves to the upper on the wipers. Since a shoe prior to the toe-lasting operation is commonly lasted at the sides of the forepart beyond the toe portion, and since the margin of the upper may, therefore, be more readily outspread and clamped on the toe wipers about the end of the toe than at the sides of the toe near the previously lasted portions when the wipers are in the positions which they occupy at the beginning of the wiping of the upper heightwise of the last (commonly known as the upwiping operation), the above-mentioned upper-clamping members are positioned initially in such relation to one another heightwise of the last as to clamp the upper on the wipers first about the end of the toe and thereafter successively in locations farther from the end of the toe and nearer the pre-

viously side-lasting portions of the shoe in the course of the upwiping operation. This avoids any such displacement of the margin of the upper heightwise of the last near the previously side-lasting portions as might tend to produce wrinkles at the sides of the toe. The construction shown is further such that a more effective pull is applied to the upper by the wipers and the retarder at the corners of the toe, where the customary 10 pulling-over operation previously performed is comparatively ineffective, than in other locations about the toe. For this purpose the upper-clamping members at the corners of the toe are controlled by stronger springs than the other 15 members.

To insure that the margin of the upper will be properly outspread and smoothly clamped on the wipers, the construction herein shown further includes novel means for moving the retarder, or 20 portions thereof, outwardly over the wipers. As illustrated, the portions of the retarder which clamp the upper at the sides of the toe are mounted to move in directions widthwise of the last relatively to the portion at the end of the toe 25 and are thus moved outwardly over the wipers by means responsive to pressure applied thereto by the wipers in the course of the upwiping operation. The retarder as a whole is, moreover, moved lengthwise of the last to apply a similar outward wipe to the margin of the upper about the end of the toe by novel means responsive to movement of the retarder heightwise of the last by the wipers.

The above and other features of the invention, 35 including various novel details of construction and combinations of parts, will now be more particularly described with reference to the accompanying drawings and thereafter pointed out in the claims.

40 In the drawings, Fig. 1 is a view mainly in right-hand side elevation of a portion of the machine shown in the previously mentioned Letters Patent as modified for purposes of the present invention;

45 Fig. 2 is a plan view of the retarder, illustrating its relation to the toe end of a shoe shown diagrammatically;

Fig. 3 is a section on the line III—III of Fig. 2;

Fig. 4 is a section on the line IV—IV of Fig. 2;

50 Fig. 5 is a view showing mainly the retarder as it appears in rear elevation;

Fig. 6 is mainly a vertical sectional view from the right of the machine, showing the retarder and parts associated therewith, together with the wipers and shoe-positioning means, the parts be-

ing shown in the positions which they occupy prior to the beginning of the toe-lasting operation;

Fig. 7 is a view similar to Fig. 6, showing the parts as they appear substantially at the beginning of the upwiping operation of the wipers on the upper;

Fig. 8 is a view also similar to Fig. 6, showing the parts as they appear just after the beginning of the movements of the wipers to wipe the marginal portion of the upper inwardly over the insole;

Fig. 9 is mainly a plan view showing the retarder and the wipers in the same positions as in Fig. 8; and

Fig. 10 is a view in right-hand side elevation, showing means additional to that shown in Fig. 1 for controlling the retarder.

In view of the disclosure in the above-mentioned Letters Patent, only such portions of the machine will be herein described as it is necessary to refer to for an understanding of the invention. In the construction herein shown the position of a welt shoe in the machine is determined by shoe-positioning means constructed as disclosed in Letters Patent No. 2,388,367, granted on November 6, 1945, on an application of mine, this shoe-positioning means comprising a pair of members 2 (Figs. 1 and 9) relatively adjustable for shoes of different sizes and styles and arranged to engage the inner face of the toe-end portion of the lip *a* of the insole and also the bottom face of the insole adjacent to the lip. Against the members 2 the shoe is clamped by a toe rest 4 which is moved upwardly into clamping position shortly after the beginning of the cycle of power operations of the machine. For lasting the toe end of the shoe the machine is provided with a pair of wipers 6 which are advanced and closed to embrace the upper about the toe end of the last and are swung upwardly about an axis (not shown) extending widthwise of the last to wipe the upper heightwise of the last. Thereafter the wipers are further advanced and closed to wipe the marginal portion of the upper inwardly over the feather and against the lip of the insole, the lip being supported against the inward pressure of the wipers by the members 2.

In the machine herein shown the grippers disclosed in Letters Patent No. 2,160,846 for applying a pull to the toe end of the upper and for controlling it in the toe-lasting operation are dispensed with. Instead of such grippers there is provided a retarder identified generally by the reference character 8, the construction of which will be hereinafter described in detail, this retarder being arranged to clamp the marginal portion of the toe end of the upper outspread on the wipers and to control the upper in the course of the wiping movements of the wipers. The retarder includes a block 10 on which other portions thereof are supported, this block being adjustable in directions lengthwise of the shoe along a dovetailed guideway 12 (Fig. 5) provided in the lower split end of an upwardly extending rectangular bar 14. A screw 16 threaded in the lower end of the bar serves by contraction of the split portion of the bar to clamp the block 10 in adjusted position. The bar 14 is vertically movable in a U-shaped guide 18 which is secured by screws 20 to a boss 22 formed on a frame casting 24 with which the machine is provided. A pin 26 mounted in the upper end of the guide 18 and extending through a slot 28 in the bar 14 further assists in guiding the bar in its downward and upward

movements. Secured to the rear of the guide 18 is the upper end portion of a downwardly extending leaf spring 30 the lower end portion of which bears against the rear face of the bar 14 near the lower end portion of the guide and tends to hold the bar pressed forwardly against that portion of the guide.

The upper end of the bar 14 is connected by a link 32 (Fig. 1) to one arm 34 of a two-armed lever 36 loosely mounted on a rockshaft 38 supported in bearings on the frame 24. The other arm 40 of the lever 36 is connected by a spindle 42 to one arm 44 of a two-armed lever 46 fast on the rockshaft 38. The spindle 40 is mounted to turn in a trunnion block 48 pivotally mounted on the arm 40 and is threaded in another trunnion block 50 pivotally mounted on the arm 44. By means of a collar 52 and a hand wheel 54 engaging the trunnion block 48 on its opposite sides the spindle is prevented from moving lengthwise relatively to this block, and accordingly turning movement thereof serves to adjust the two-armed lever 36 about the rockshaft 38 and thereby through the link 32 to adjust the bar 14 and the retarder 8 in either a downward or an upward direction. Fast on one end of the rockshaft 38 is an arm 56 connected by a downwardly extending link 58 to one arm 60 (Fig. 10) of a bell-crank lever 62 mounted to turn about a shaft 64. The other arm 66 of this bell-crank lever is provided with a roll 68 in engagement with the periphery of a cam 70 fast on the main cam shaft 72 of the machine. A spring 74 connected to the arm 66 tends to swing the bell-crank lever 62 in a counterclockwise direction (Fig. 10) and holds the roll 68 normally against the cam. At the proper time in the operation of the machine a drop *b* on the cam permits the spring 74 to swing the lever 62 in the direction to impart downward movement through the rockshaft 38 and the arm 34 to the bar 14 and the retarder 8 and thus to move the retarder into position to clamp the margin of the upper outspread on the wipers 6 (Fig. 7). In thus moving the retarder downwardly the spring 74 is assisted by another spring 76 (Fig. 1) connected at its lower end to a second arm 78 of the two-armed lever 46 and at its upper end to a lever 80 which is used adjustably to vary the tension of the spring 76 and is like the lever 72 shown in Letters Patent No. 2,303,342, granted on December 1, 1942, on an application of F. C. Eastman.

The retarder 8 is provided with a plurality of fingers 82 arranged to engage the upper in a series about the end and along the sides of the toe. The lower end portions of these fingers are approximately rectangular in shape, except for curved recesses 84 (Fig. 4) in their outer sides to restrict the area of engagement of their lower end faces with the upper. Extending upwardly from their lower end portions the fingers have hollow, cylindrical portions parallel to one another and within which are mounted coil springs 86 tending to force the fingers downward independently of one another. Within these coil springs are upwardly extending rods 88 fast in the lower end portions of the fingers. One group of the fingers 82, herein shown as six in number, is arranged to engage the upper about the end 70 of the toe, these fingers being supported on the block 10 of the retarder and their cylindrical portions being slidably mounted in the block. Secured to the block is a cap 90 against which the upper ends of the springs 86 controlling the fingers of this group are seated, and the rods 88

secured to these fingers extend upwardly through the cap and have on their upper ends nuts 92 which by engagement with the cap determine adjustably the initial positions of the fingers relatively to the block 10. Beyond the above-mentioned end group of fingers 82 are two other groups arranged to engage the upper respectively along the opposite sides of the toe, these groups of fingers being supported respectively by arms 94 which are pivotally mounted for swinging movements widthwise of the shoe on studs 96 mounted in the block 10 and extending heightwise of the shoe in locations beyond the end of the toe. The cylindrical portions of the fingers 82 of these side groups are slidably mounted in the corresponding arms 94, and secured to each arm is a bracket 98 against which the upper ends of the corresponding springs 86 are seated and by engagement with which nuts 92 on the corresponding rods 88 serve to determine adjustably the initial positions of the fingers relatively to one another heightwise of the shoe. A spring 100 looped about the studs 96 bears against the outer sides of the brackets 98 and tends to swing the arms 94 inwardly toward each other. The initial positions of the arms 94 widthwise of the shoe are determined adjustably by screws 102 which are threaded in the arms and bear at their inner ends against spreaders 104 pivotally mounted respectively on the two studs 96, the positions of these spreaders being determined by a wedge member 106 located between them. This wedge member is controlled by a spring 108 which tends to move it downwardly, the limit of its downward movement being determined by the engagement of shoulders 110 (Fig. 3) thereon with the top faces of the spreaders 104. The lower end of the wedge member 106 is arranged to engage the margin of the upper outspread on the wipers at the end of the toe and thereby to cause wedge faces 112 formed on its opposite sides to swing the spreaders 104 and the arms 94 outwardly in predetermined time relation to the operation of the wipers on the toe end of the upper; as more particularly hereinafter explained, thus causing the two side groups of fingers 82 to spread and wipe the margin of the upper at the sides of the toe outwardly over the wipers.

In predetermined time relation also to the movements of the wipers a movement lengthwise of the shoe is imparted to the retarder 8 as a whole to cause the fingers 82 located about the end of the toe to have an outward wiping action on the margin of the upper. For this purpose there is located in a recess 114 in the bar 14 a pawl 116 mounted to swing about a pin 118 in the bar and controlled by two oppositely acting springs 120 which tend to hold it in a substantially horizontal position with its front end extending into a recess 122 in the guide 18. When the bar 14 is moved downwardly to carry the retarder toward the wipers the pawl 116 is carried to a position where its front end engages ratchet teeth 124 formed on the lower end portion of the guide 18, the pawl being then inclined in a forward and upward direction (Fig. 7). Upward movement of the retarder and the bar 14 which occurs in the course of the toe-lasting operation, as more particularly hereinafter explained, causes the pawl in engagement with the ratchet teeth to swing toward a horizontal position and thereby to force the lower end portion of the bar and with it the retarder rearwardly against the resistance of the spring 30, as illus-

trated in Fig. 8. To permit such movement of the bar 14 a bevel 126 (Fig. 6) is formed on the upper end portion of the guide 18 near the pin 28.

In the operation of the machine, in so far as it is of interest with reference to the present invention, the shoe is first clamped against the shoe-positioning members 2 by upward movement of the toe rest 4, after which the wipers 6 are advanced and closed and are swung upwardly to bring their edges into positions for thereafter effectively wiping the upper heightwise of the last. In the course of these movements of the wipers the drop b on the cam 10 arrives in a position opposite the roll 68 and the retarder 8 is moved rectilinearly downward toward the wipers by the action of the springs 14 and 76 on the rockshaft 38. The fingers 82 of the group located at the end of the toe, which may be adjusted by the corresponding nuts 92 with their lower end faces at the same height, first arrive in positions to clamp the margin of the upper outspread on the wipers, as illustrated in Fig. 7. This is not only because of the inclination of the wipers lengthwise of the shoe at this stage in the lasting operation, but also because the fingers of the two groups along the sides of the toe are, as shown, so adjusted by their nuts 92 that they are positioned successively higher the farther they are from the end of the toe. Since the margin of the upper along the sides of the toe is inclined upwardly toward the portions already lasted over the insole beyond the toe, this arrangement of the side fingers 82 serves to prevent the margin of the upper in these locations from being unduly displaced until the wipers have been moved upwardly far enough to permit it to be readily clamped thereon. As the wipers continue their upward movements the fingers about the end of the toe are forced upwardly against the resistance of their springs 86, and the fingers along the sides of the toe become successively effective to clamp the upper on the wipers in locations progressively farther from the end of the toe. In the course of the upwiping operation, moreover, outward swinging movements are imparted to the arms 94 which carry the side groups of fingers in response to pressure of the margin of the upper at the end of the toe on the wedge member 106 which is moved upwardly by the wipers. Insurance is thus afforded that the margin of the upper along the sides of the toe will be properly outspread over the wipers and that it will be clamped smoothly on the wipers by reason of the outward wiping action of the fingers 82 thereon. Before the completion of the upwiping operation the enlarged lower end portions of the fingers 82 engage the lower faces of the block 10 and the arms 94, after which the retarder as a whole and its supporting bar 14 are moved upwardly by the wipers against the stronger resistance of the springs 14 and 76, the rockshaft 38 turning in a clockwise direction and the roll 68 (Fig. 10) being moved out of contact with the cam 10. At this time the pawl 116, which was carried downwardly by the downward movement of the bar 14 to an inclined position in engagement with the teeth 124, as shown in Fig. 7, is turned about its pin 118 by the action of the teeth 124 thereon and thereby forces the lower end of the bar 14 and the retarder in a rearward direction to cause the fingers 82 about the end of the toe to have an outward wiping action on the margin of the upper in that location as further insurance that the upper will be smoothly clamped free from

wrinkles on the wipers. After the upwiping operation the wipers are further advanced and closed to wipe the marginal portion of the upper inwardly over the feather and against the lip of the insole, and shortly after the beginning of their inward movements, when they are positioned, for example, as shown in Fig. 8, a rise c on the cam 70 acts on the roll 68 to turn the rockshaft 38 farther in a clockwise direction and thus to lift the bar 14 and to carry the retarder away from the upper and the wipers. As the bar 14 is thus moved upwardly the pawl 116 is first swung downwardly by the action of the teeth 124 thereon to permit the lower end portion of the bar to be returned by the spring 30 to its normal position relatively to the guide 18 , and the pawl is then carried upwardly into position to permit its front end again to enter the recess 122 in the guide and to permit it again to be centralized by the springs 120 . It will be understood that as the retarder is moved upwardly away from the wipers the wedge member 103 is returned to its initial position by the spring 108 and the arms 94 carrying the side groups of fingers are swung inwardly by the spring 100 to the positions determined by the screws 102 .

It will be understood that a shoe operated upon by the machine herein shown will ordinarily have received a pulling-over operation at an earlier stage in its manufacture. Since the pulling-over operation as performed in accordance with the usual commercial practice applies no direct pull to the upper at the corners of the toe, the construction herein shown is such that the wipers and the retarder apply a stronger pull to the upper in those locations than in other locations. For this purpose the springs 88 which press the fingers 82 at the corners of the toe on the upper are stronger springs than those controlling the other fingers. Such stronger springs may be used, for example, to control the two fingers of the end group which are farthest from the center of the toe and that finger of each side group which is nearest the end of the toe.

Having described the invention, what I claim as new and desire to secure by Letters Patent of the United States is:

1. In a lasting machine, the combination with means for wiping the toe-end portion of an upper on a last heightwise of the last, of a retarder for clamping the marginal portion of the upper outspread on said wiping means about the end and along the sides of the toe, said retarder including at the sides of the toe a plurality of upper-clamping members relatively movable in response to pressure of the upper on some of them in the course of the wiping of the upper heightwise of the last to render others thereof located farther from the end of the toe effective also to clamp the upper.

2. In a lasting machine, the combination with means for wiping the toe-end portion of an upper on a last heightwise of the last, of a retarder for clamping the marginal portion of the upper outspread on said wiping means about the end and along the sides of the toe, said retarder including at each side of the toe a plurality of upper-clamping members arranged in different positions lengthwise of the last and relatively movable heightwise of the last to adjust themselves to the upper on the wipers, the members at each side of the toe being initially positioned in such offset relation heightwise of the last as to render them effective successively to clamp the upper in locations farther from the end of the toe in

the course of the wiping of the upper heightwise of the last.

3. In a lasting machine, the combination with means for wiping the toe-end portion of an upper on a last heightwise of the last, of a retarder for clamping the marginal portion of the upper outspread on said wiping means about the end and along the sides of the toe, said retarder including at each side of the toe a plurality of upper-clamping members arranged in different positions lengthwise of the last and relatively movable heightwise of the last to adjust themselves to the upper on the wipers, springs associated respectively with said different members for pressing them on the upper while permitting their relative movements, and means arranged to cooperate with said springs to position the members at each side of the toe adjustably in such offset relation heightwise of the last as to render them effective successively to clamp the upper in locations farther from the end of the toe in the course of the wiping of the upper heightwise of the last.

4. In a lasting machine, the combination with wipers movable to wipe the toe-end portion of an upper on a last heightwise of the last, of a retarder for clamping the marginal portion of the upper outspread on the wipers about the end and along the sides of the toe, said retarder including at each side of the toe a plurality of upper-clamping members arranged in a series lengthwise of the last and each yieldingly movable heightwise of the last by the wipers, and means for positioning the members at each side of the toe initially in such offset relation to one another heightwise of the last as to cause them to clamp the upper successively in locations farther from the end of the toe in the course of the wiping of the upper heightwise of the last.

5. In a lasting machine, the combination with wipers movable to wipe the toe-end portion of an upper on a last heightwise of the last, of a retarder for clamping the marginal portion of the upper outspread on the wipers about the end and along the sides of the toe, said retarder including at each side of the toe a plurality of upper-clamping members arranged in a series lengthwise of the last, springs associated respectively with said different members and against the resistance of which they are movable heightwise of the last independently of one another by the wipers, and means for adjustably positioning the members at each side of the toe initially in such offset relation to one another heightwise of the last as to cause them to clamp the upper successively in locations farther from the end of the toe in the course of the wiping of the upper heightwise of the last.

6. In a lasting machine, the combination with wipers movable upwardly to wipe the toe-end portion of an upper heightwise of a last positioned bottom upward, of a retarder for clamping the marginal portion of the upper outspread on the wipers about the end and along the sides of the toe, said retarder including at each side of the toe a plurality of upper-clamping members arranged in a series lengthwise of the last, said members being upwardly movable independently of one another in response to pressure of the upper thereon, and means for initially positioning the members at each side of the toe at different heights to render them effective to clamp the upper successively in locations farther from the end of the toe in the course of the wiping of the upper heightwise of the last.

7. In a lasting machine, the combination with wipers for wiping the toe-end portion of an upper on a last heightwise of the last, of a retarder for clamping the marginal portion of the upper outspread on the wipers, said retarder comprising a plurality of upper-clamping members arranged in a series about the end and along the sides of the toe and relatively movable heightwise of the last to adjust themselves to the upper on the wipers, said members being positioned in such relation to one another as to clamp the upper first about the end of the toe and thereafter along the sides of the toe successively in locations farther from the end of the toe in response to relative movements thereof in the course of the wiping of the upper heightwise of the last.

8. In a lasting machine, the combination with wipers movable to wipe the toe-end portion of an upper on a last heightwise of the last, of a retarder for clamping the marginal portion of the upper outspread on the wipers, said retarder comprising a plurality of upper-clamping members arranged in a series about the end and along the sides of the toe, springs against the resistance of which said members are movable independently of one another heightwise of the last by the wipers, and means for positioning said members initially in such relation to one another heightwise of the last as to cause them to clamp the upper first about the end of the toe and to render the members at the sides of the toe thereafter effective to clamp the upper successively in locations farther from the end of the toe in the course of the wiping of the upper heightwise of the last.

9. In a lasting machine, the combination with wipers for wiping an upper about the toe end of a last into lasted position, of a retarder for clamping the marginal portion of the upper outspread on the wipers to control it in the lasting operation, said retarder comprising a plurality of fingers arranged to extend longitudinally heightwise of the last in a series about the end and along the sides of the toe and each having an end face for engaging and clamping the upper, said fingers being relatively movable rectilinearly heightwise of the last in parallel relation to one another to permit them to adjust themselves to the upper on the wipers.

10. In a lasting machine, the combination with wipers for wiping an upper about the toe end of a last into lasted position, of a retarder for clamping the marginal portion of the upper outspread on the wipers to control it in the lasting operation, said retarder comprising a plurality of fingers arranged to extend longitudinally heightwise of the last in a series about the end and along the sides of the toe and each having an end face for engaging and clamping the upper, said fingers being relatively movable heightwise of the last in parallel relation to one another to permit them to adjust themselves to the upper on the wipers, springs associated respectively with the different fingers for pressing them on the upper, and means for relatively adjusting said fingers heightwise of the last.

11. In a lasting machine, the combination with wipers for wiping the toe-end portion of an upper on a last heightwise of the last, of a retarder for clamping the marginal portion of the upper outspread on the wipers, said retarder comprising a plurality of fingers arranged to extend longitudinally heightwise of the last in a series about the end and along the sides of the toe and each having an end face for engaging and

clamping the upper, said fingers being relatively movable heightwise of the last to adjust themselves to the upper on the wipers, and means for positioning the fingers initially in such relation to one another as to clamp the upper first about the end of the toe and thereafter along the sides of the toe successively in locations farther from the end of the toe in response to relative movements thereof in the course of the wiping of the upper heightwise of the last.

12. In a lasting machine, the combination with wipers movable to wipe the toe-end portion of an upper on a last heightwise of the last, of a retarder for clamping the marginal portion of the upper outspread on the wipers, said retarder comprising a plurality of upper-clamping members arranged in a series about the toe, and a support for said members relatively to which they are yieldingly movable heightwise of the last by the wipers, said support and members being thereafter further movable as a unit by the wipers in the course of the wiping of the upper heightwise of the last.

13. In a lasting machine, the combination with wipers movable to wipe the toe-end portion of an upper on a last heightwise of the last, of a retarder for clamping the marginal portion of the upper outspread on the wipers, said retarder comprising a plurality of upper-clamping members arranged in a series about the toe, springs associated respectively with said different members and against the resistance of which they are yieldingly movable heightwise of the last by the wipers, a support for said members relatively to which they are thus movable, and additional spring means against the resistance of which said support and members are further movable as a unit by the wipers in the course of the wiping of the upper heightwise of the last.

14. In a lasting machine, the combination with means for wiping the toe-end portion of an upper on a last heightwise of the last, of means for clamping the marginal portion of the upper on said wiping means about the end and along the sides of the toe to apply a pull to the upper as it is wiped heightwise of the last, said clamping means being so constructed as to cause the upper to be pulled more forcibly where it is clamped at the corners of the toe than where it is clamped at the extreme end and the sides of the toe.

15. In a lasting machine, the combination with means for wiping the toe-end portion of an upper on a last heightwise of the last, of a retarder for clamping the marginal portion of the upper on said wiping means about the end and along the sides of the toe to apply a pull to the upper as it is wiped heightwise of the last, said retarder having means for clamping the upper with a comparatively high degree of force at the corners of the toe and with less force at the extreme end and the sides of the toe.

16. In a lasting machine, the combination with wipers for wiping the toe-end portion of an upper on a last into lasted position, of a retarder for clamping the marginal portion of the upper on said wipers about the end and along the sides of the toe to control it in the lasting operation, said retarder having means for applying a comparatively high degree of clamping pressure to the upper at the corners of the toe and less clamping pressure thereto at the extreme end and the sides of the toe.

17. In a lasting machine, the combination with wipers for wiping the toe-end portion of an upper on a last into lasted position, of a retarder for

clamping the marginal portion of the upper on said wipers about the end and along the sides of the toe to control it in the lasting operation, said retarder including a plurality of upper-clamping members arranged to engage the upper in a series substantially all around the toe, and springs associated respectively with said different members for pressing them on the upper, the springs controlling the members engaging the upper at the corners of the toe being stronger than the springs controlling the members at the extreme end and the sides of the toe.

18. In a lasting machine, the combination with means for wiping the toe-end portion of an upper on a last heightwise of the last, of devices arranged to clamp the marginal portion of the upper outspread on said wiping means at the sides of the toe, and means for moving said devices outwardly over the wiping means widthwise of the last in clamping engagement with the upper in the course of the wiping of the upper heightwise of the last.

19. In a lasting machine, the combination with wipers for wiping the toe-end portion of an upper on a last heightwise of the last, of devices arranged to clamp the marginal portion of the upper outspread on the wipers at the sides of the toe in locations progressively farther from the end of the toe in the course of the wiping of the upper heightwise of the last, and means for moving said devices outwardly over the wipers widthwise of the last as they thus progressively clamp the upper on the wipers.

20. In a lasting machine, the combination with wipers for wiping the toe-end portion of an upper on a last heightwise of the last, of devices arranged to clamp the marginal portion of the upper outspread on the wipers at the sides of the toe, said devices each including a plurality of upper-engaging members arranged in a series lengthwise of the last and relatively movable to clamp the upper successively in locations farther from the end of the toe in the course of the wiping of the upper heightwise of the last, and means for moving said devices outwardly over the wipers widthwise of the last as they thus act on the upper.

21. In a lasting machine, the combination with wipers for wiping the toe-end portion of an upper on a last heightwise of the last, of a group of upper-engaging members arranged to clamp the marginal portion of the upper outspread on the wipers at the end of the toe, other groups of upper-engaging members arranged to clamp the marginal portion of the upper outspread on the wipers at the sides of the toe, and means for moving said other groups outwardly over the wipers widthwise of the last relatively to said first-named group in the course of the wiping of the upper heightwise of the last.

22. In a lasting machine, the combination with wipers for wiping an upper about the toe end of a last into lasted position, of devices arranged to clamp the marginal portion of the upper on the wipers at the sides of the toe to control it in the lasting operation, and means responsive to pressure applied thereto by the wipers for moving said devices outwardly widthwise of the last.

23. In a lasting machine, the combination with wipers for wiping an upper about the toe end of a last into lasted position, of devices arranged to clamp the marginal portion of the upper outspread on the wipers at the sides of the toe to control it in the lasting operation, and mecha-

nism responsive to engagement of the margin of the upper on the wipers therewith for moving said devices outwardly over the wipers widthwise of the last.

5 24. In a lasting machine, the combination with wipers for wiping an upper about the toe end of a last into lasted position, of devices arranged to clamp the marginal portion of the upper outspread on the wipers at the sides of the toe to control it in the lasting operation, means supporting said devices and movable to carry them heightwise of the last toward the wipers, and mechanism carried by said supporting means and arranged to be rendered operative by pressure applied thereto by the wipers for moving said devices outwardly over the wipers widthwise of the last.

10 25. In a lasting machine, the combination with wipers movable to wipe an upper about the toe end of a last heightwise of the last, of devices arranged to clamp the marginal portion of the upper outspread on the wipers at the sides of the toe, and mechanism operative in response to the movement of the wipers heightwise of the last 20 to move said devices outwardly over the wipers widthwise of the last.

15 26. In a lasting machine, the combination with wipers for wiping an upper about the toe end of a last into lasted position, of devices arranged to 30 clamp the marginal portion of the upper outspread on the wipers at the sides of the toe to control it in the lasting operation, members supporting said devices and mounted for movements widthwise of the last, and a wedge member between said supporting members for forcing them apart to move said devices outwardly over the wipers in the lasting operation.

20 27. In a lasting machine, the combination with wipers for wiping an upper about the toe end of a last into lasted position, of devices arranged to 40 clamp the marginal portion of the upper outspread on the wipers at the sides of the toe to control it in the lasting operation, arms supporting said devices and mounted for swinging movements widthwise of the last, and a wedge member arranged to be rendered operative by pressure applied thereto by the wipers to force said arms apart and thereby to move said devices outwardly over the wipers.

25 28. In a lasting machine, the combination with wipers for wiping an upper about the toe end of a last heightwise of the last, of a retarder for clamping the marginal portion of the upper outspread on the wipers about the end and along the sides of the toe, and means for moving portions of said retarder lengthwise and widthwise of the last respectively to wipe the marginal portion of the upper outwardly over the wipers in the course of the wiping of the upper heightwise of the last by the wipers.

35 29. In a lasting machine, the combination with wipers for wiping an upper about the toe end of a last heightwise of the last, of a retarder for clamping the marginal portion of the upper outspread on the wipers about the end and along the sides of the toe, and means for moving said retarder as a whole lengthwise of the last and for also moving portions thereof at the sides of the toe widthwise of the last to wipe the marginal portion of the upper outwardly over the wipers lengthwise and widthwise of the last in the course of the wiping of the upper heightwise of the last by the wipers.

70 30. In a lasting machine, the combination with

wipers movable to wipe an upper about the toe end of a last heightwise of the last, of a retarder for clamping the marginal portion of the upper outspread on the wipers about the end and along the sides of the toe, and means responsive to the movement of the wipers heightwise of the last to move portions of said retarder at the end and the sides of the toe respectively lengthwise and widthwise of the last to wipe the marginal portion of the upper outwardly over the wipers.

31. In a lasting machine, the combination with wipers movable to wipe an upper about the toe end of a last heightwise of the last, of a retarder for clamping the marginal portion of the upper outspread on the wipers about the end and along the sides of the toe, and means responsive to the movement of the wipers heightwise of the last to move said retarder as a whole lengthwise of the last and to move portions thereof at the sides of the toe widthwise of the last to wipe the marginal portion of the upper outwardly over the wipers lengthwise and widthwise of the last.

32. In a lasting machine, the combination with wipers for wiping an upper about the toe end of a last into lasted position, of a retarder for clamping the marginal portion of the upper outspread on the wipers about the end and along the sides of the toe to control it in the lasting operation, means responsive to pressure applied thereto by the wipers for moving portions of said retarder at the sides of the toe outwardly over the wipers widthwise of the last, and additional means also controlled by the wipers for moving said retarder as a whole lengthwise of the last outwardly over the margin of the upper on the wipers.

33. In a lasting machine, the combination with

wipers movable to wipe an upper about the toe end of a last heightwise of the last, of a retarder for clamping the marginal portion of the upper outspread on the wipers, said retarder being movable heightwise of the last by the wipers, and a pawl arranged to turn in response to that movement of the retarder to force the retarder also outwardly over the wipers.

34. In a lasting machine, the combination with
10 wipers movable to wipe an upper about the toe end of a last heightwise of the last, of a retarder for clamping the marginal portion of the upper outspread on the wipers, a member supporting said retarder and movable with it heightwise of the last by the wipers, a member along which said supporting member is thus movable, a pawl pivotally mounted on one of said members, and means on the other member for engaging and turning said pawl to cause the pawl to force the retarder outwardly over the wipers in response to its movement heightwise of the last.

35. In a lasting machine, the combination with
20 wipers movable to wipe an upper about the toe end of a last heightwise of the last, of a retarder for clamping the marginal portion of the upper outspread on the wipers, a support for said retarder movable to carry it heightwise of the last toward the wipers and reversely movable thereafter with the retarder by the wipers, a pawl pivotally mounted on said support, and means for
25 engaging and turning said pawl to force the retarder outwardly over the wipers in response to such reverse movement of the support and retarder.
